IRONING MACHINE

Gustave Vercammen, Gand, Belgium

Application November 29, 1951, Serial No. 258,814

Claims priority, application Belgium May 30, 1951

4 Claims. (Cl. 38—9)

1

The present invention relates to ironing machines, and more particularly to a machine for ironing a material.

It is an object of the present invention to render the ironing machine continuous in operation.

It is another object of the present invention to reduce the costs connected with the control and the maintenance of the ironing machine.

It is a further object of the present invention to increase the efficiency of the ironing machine.

It is still another object of the present invention to reduce the number of attendants required for an operation of the ironing machine.

An ironing machine according to the present invention comprises in its broadest aspects an ironing cylinder, a countermember arranged with respect to the ironing cylinder so as to define an ironing space between the ironing cylinder and the countermember, the ironing cylinder and the countermember being heated by gas, and means for carrying the material to be ironed through the ironing space between the ironing cylinder and the countermember, the carrying means conveying the material further into a zone in which it can be reached by hand by an operator charged with the collecting of the material after ironing.

The countermember can be designed either as a countercylinder or as a part having a preferably part-cylindrical recess.

A preferred embodiment of the present invention comprises in combination an elongated table, a gas-heated part arranged across the table, the gas-heated part having a part-cylindrical recess arranged at the upper surface thereof, a gas-heated ironing cylinder having a length substantially corresponding to the width of the table, and being arranged above the part so as to define with the recess thereof a part-cylindrical ironing space, a first roller and a second roller arranged, respectively, at the front and rear ends of the table, an endless band passing over the first roller, the table, through the ironing space between the ironing cylinder and the part and over the second roller, and means for automatically controlling the tension of the endless band, whereby the material to be ironed is carried by the endless band through the ironing space between the gas-heated part and the gas-heated ironing cylinder and is further conveyed to a zone in which it can be reached by hand by an operator charged with the collecting of the material after ironing.

Preferably the endless band has a width being

2

substantially equal to the width of the table and the length of the ironing cylinder.

In a preferred embodiment of the present invention a hem is arranged along the edge of the endless band and a curved bar preferably consisting of metal is arranged with respect to one of the rollers so as to surround part of the perimeter near one end thereof, the bar engaging the hem of the endless band so as to guide the same.

10 Preferably an annular groove is provided near the end of the roller associated with the curved bar, the annular groove holding the bar in position on the roller.

In a preferred embodiment of the present invention the ironing cylinder has the shape of a hollow metal drum arranged horizontally and non-rotatably and a gas pipe having a plurality of lateral apertures is arranged horizontally in the hollow drum at a position being angularly disposed by 25 to 40° with respect to the vertical through the longitudinal axis of the drum so that the drum is heated by the gas escaping from the apertures of the pipe in places spaced apart from the crest of the drum. Preferably the drum has a polished outer surface devoid of any covering material.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a diagrammatic side elevation of an ironing machine according to the invention;

Fig. 2 is an end elevation on an enlarged scale of the roller at the front end of the machine shown in Fig. 1;

Fig. 3 is a partial side elevation on an enlarged scale of the roller shown in Fig. 2;

Fig. 4 is an end elevation on an enlarged scale of the ironing cylinder shown in the machine in Fig. 1; and

Fig. 5 is a sectional side elevation on an enlarged scale of part of Fig. 1.

Referring now to the drawing and first to Fig. 1, the table 1 of the machine consisting of any suitable material is provided with a smooth surface and is arranged in the usual manner on an understructure (not shown). The table 1 is provided with a countermember, preferably a metallic part 2 forming a part-cylindrical recess and being heated by gas as shown in Fig. 5 in

which the part 2 is heated by a gas pipe 20. Above the recess of the part 2 is arranged the ironing cylinder 3 which is equally heated by gas as more fully explained hereinafter. It should be understood however, that the part 2 can be replaced, if desired, by a counter-cylinder heated by gas. The ironing cylinder 3 is supported by bearing blocks 21 (Fig. 5) movable in a groove of the frame 22 so as to allow a displacement along the vertical according to the thickness of the material to be ironed. At the both ends of the table 1 rollers 4 and 5 having axes, respectively, substantially parallel to the axis of the ironing cylinder 3 and consisting of wood, caoutchouc, metal or plastic material are provided, respectively, which are supported by bearings (not shown) which allow a free rotation of the rollers. Below the table 1 stretching rollers 6 and 7 are arranged one of which is driven by a motor (not shown). The axes of the rollers are arranged substantially parallel to the axes of the rollers 4 and 5. An endless band 8 having a width substantially equal to that of the table 1 and to the length of the cylinder 3 passes between the cylinder 3 and the part 2 of the table 1 and around the rollers 4, 5, 6 and 7 so that the upper part of the band 8 is supported above the table by the rollers 4 and 5 between which the upper part of the band 8 enters the space between the part 2 and cylinder 3. The lower part of the band 8 passes around the stationary rollers 7 and 6 underneath the table. The tension of the endless band 8 can be automatically adjusted, e. g. by automatically adjusting the distance of the rollers 4, 5 or the like.

The endless band 8 consisting of textile material such as cotton, linen, silk, rayon, nylon, or the like, is provided along one or each edge thereof with a hem a few centimeters wide which is engaged by a metal bar 9 which can be round, half round, or flat and is bent back around one of the rollers 4 or 5, preferably around the roller 4 being arranged at the front end of the table 1. In said roller, preferably near each of the extremities thereof, an annular groove 10 is provided which serves together with the table 1 for holding the bar 9 in position (Figs. 2 and 3). The band 8 is in consequence thereof guided by the hem thereof on the bar 9. It should be understood that a similar bar (not shown) is disposed along the other edge of the band 8 so that the latter is perfectly guided and cannot crease or displace itself under the ironing cylinder 3; the width of the band 8 is stabilized and its course is rectilinear.

Referring now to Figs. 4 and 5, the ironing cylinder 3 is shaped as a hollow drum consisting of iron or steel and is heated by means of the flames caused by gas escaping through lateral apertures of a gas tube or pipe 11 which is arranged horizontally and in a position being displaced to the vertical by an angle between 25° and 40° as clearly shown in Fig. 4 in order to improve the combustion of the gas. In fact, in the position of the gas pipe 11 shown in the drawings, the flames do not burn near the crest of the cylinder 3 where the air is poor in oxygen and mixed with burnt gases but in immediate proximity of the internal wall of the cylinder 3 at places further down in a pure atmosphere formed by the continually arriving fresh air which passes through the lateral flanges of the cylinder 3, whereas the burnt gases accumulate in the upper part of the cylinder 3 before escaping from the same.

The gas pipe 11 can be fed with coal gas, 75 same, whereby the material to be ironed is car-

"butagas" (supplied in bombs) or with any other combustible gas.

The outer surface of the cylinder 3 is polished and not provided with any cover such as those conventionally used in the majority of ironing machines.

The operation of this machine is as follows:

The material to be ironed is placed on the band 8 so that it occupies the total width of the part of the upper portion of the band 8 supported by the table 1 and situated before the ironing cylinder 3. The width of the band 8 and consequently of the table 1 are conveniently chosen and may have any suitable value. The material is conveyed by the band 8 to the cylinder 3 and guided underneath the latter so that it is ironed in the ironing space between the cylinder 3 and the recessed part 2 which are both heated by gas. After passing underneath the cylinder 3 the ironed material which is still carried by the band 8 is conveyed to a zone in which the material can be reached by the hands of the operator charged with collecting the material after ironing. The machine thus allows a "continuous" ironing over the whole length of the cylinder 3 and requires a very reduced attendance by personnel. Actually only two persons are required for operating the machine, one for putting the material to be ironed on the band 8 before it passes the cylinder 3 and the other for lifting the ironed material from the band 8 after passing the cylinder 3.

It will be understood that each of the elements described above, or two or more together, may also find a useful application in other types of ironing machines differing from the types described above.

While the invention has illustrated and described as embodied in a machine for ironing a material, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A machine for ironing a material, comprising in combination, an elongated table; a heated part arranged across said table, said heated part having a part-cylindrical recess arranged at the upper surface thereof; a heated ironing cylinder having a length substantially corresponding to the width of said table, and being arranged above said part so as to define with said recess thereof a part-cylindrical ironing space; a first roller and a second roller arranged, respectively, at the front and rear ends of said table; an endless band passing over said first roller, said table, through said ironing space between said ironing cylinder and said part and over said second roller; a hem arranged along the edge of said endless band; and a curved bar arranged with respect to one of said rollers so as to surround part of the perimeter thereof near one end thereof, said bar engaging said hem of said endless band so as to guide the

70 same, whereby the material to be ironed is car-

ried by said endless band through said ironing space between said heated part and said heated ironing cylinder and is further conveyed to a zone in which it can be reached by hand by an operator charged with the collecting of the material after ironing.

2. A machine for ironing a material, comprising in combination, an elongated table; a heated part arranged across said table, said heated part having a part-cylindrical recess arranged at the upper surface thereof; a heated ironing cylinder having a length substantially corresponding to the width of said table, and being arranged above said part so as to define with said recess thereof a part-cylindrical ironing space; a first roller and a second roller arranged, respectively, at the front and rear ends of said table; an endless band passing over said first roller, said table, through said ironing space between said ironing cylinder and said part and over said second roller; a hem arranged along the edge of said endless band; a curved bar arranged with respect to one of said rollers so as to surround part of the perimeter thereof near one end thereof, said bar engaging said hem of said endless band so as to guide the same; and an annular groove provided near the end of said roller associated with said curved bar, said annular groove holding said bar in position on said roller, whereby the material to be ironed is carried by said endless band through said ironing space between said heated part and said heated ironing cylinder and is further conveyed to a zone in which it can be reached by hand by an operator charged with the collecting of the material after ironing.

3. A machine for ironing a material, comprising in combination, an elongated table; a heated part arranged across said table, said heated part having a part-cylindrical recess arranged at the upper surface thereof; a heated ironing cylinder having a length substantially corresponding to the width of said table, and being arranged above said part so as to define with said recess thereof a part-cylindrical ironing space; a first roller and a second roller arranged, respectively, at the front and rear ends of said table; an endless band passing over said first roller, said table, through said ironing space between said ironing cylinder and said part and over said second roller; a hem arranged along the edge of said endless band; and a curved bar consisting of metal and being ar-

ranged with respect to one of said rollers so as to surround part of the perimeter thereof near one end thereof, said bar engaging said hem of said endless band so as to guide the same; and an annular groove provided near the end of said roller associated with said curved bar, said annular groove holding said bar in position on said roller, whereby the material to be ironed is carried by said endless band through said ironing space between said heated part and said heated ironing cylinder and is further conveyed to a zone in which it can be reached by hand by an operator charged with the collecting of the material after ironing.

4. A machine for ironing a material, comprising in combination, an elongated table; a heated part arranged across said table, said heated part having a part-cylindrical recess arranged at the upper surface thereof; a heated ironing cylinder having a length substantially corresponding to the width of said table, and being arranged above said part so as to define with said recess thereof a part-cylindrical ironing space; a first roller and a second roller arranged, respectively, at the front and rear ends of said table; an endless band passing over said first roller, said table, through said ironing space between said ironing cylinder and said part and over said second roller; a hem arranged along the edge of said endless band; a curved bar consisting of metal and being arranged with respect to one of said rollers so as to surround part of the perimeter thereof near one end thereof, said bar engaging said hem of said endless band so as to guide the same; and an annular groove provided near the end of said roller associated with said curved bar, said annular groove holding said bar in position on said roller, whereby the material to be ironed is carried by said endless band through said ironing space between said heated part and said heated ironing cylinder and is further conveyed to a zone in which it can be reached by hand by an operator charged with the collecting of the material after ironing.
